UNITED STATES PATENT OFFICE.

JAMES B. SLATTERY, OF BROOKLYN, NEW YORK.

DESIGN FOR A GAS HEATER.

Application filed September 17, 1926. Serial No. 19,093. Term of patent 7 years.

To all whom it may concern:

Be it known that I, JAMES B. SLATTERY, a citizen of the United States, residing at Brooklyn, in the county of Kings and State of New York, have invented a new, original, and ornamental Design for Gas Heater, of which the following is a specification, reference being had to the accompanying drawing, forming part thereof.

The drawing shows a perspective view of the article showing my new design.

I claim:

The ornamental design for a gas heater, as shown.

JAMES B. SLATTERY.
